ARRANGEMENT FOR CONTROLLING
RECTIFIERS

Wilhelm Leukert, Berlin-Siemensstadt, Germany, assignor to Siemens-Schuckertwerke Aktiengesellschaft, Berlin-Siemensstadt, Germany, a corporation of Germany

Application April 12, 1937, Serial No. 136,342
In Germany February 5, 1936

9 Claims. (Cl. 175—363)

My invention relates to an arrangement for controlling rectifiers.

The essence of the invention consists in controlling the amount of energy of a half wave of the alternating-current supply circuit connected to a rectifier. To this end, the invention utilizes the valve effect of electric devices, particularly the valve effect of electric discharge devices. The control arrangements operating with such 10 electric discharge devices differ, however, considerably from the control arrangements hitherto employed for controlling the rectification of alternating currents.

An essential feature of the invention consists 15 in the fact that the moment at which the conducting period of an electric discharge device of a converter begins during the flow phase of the alternating voltage, is not controlled by directly influencing the conductivity of the electric discharge device, but by arranging a circuit breaker 20 in series with the electric discharge device, which circuit breaker establishes at a given moment within the half wave of the alternating voltage the conductive connection between the electric discharge device and the alternating-current supply circuit. Consequently, the electric discharge device according to the invention remains, in 25 contradistinction to the control arrangements hitherto known, isolated from the alternating-current supply circuit until the conductive period 30 is initiated, i. e., until, for instance, the arc in the case of a gas- or vapor-filled electric discharge device is started.

The usual rectifying arrangements which operate with electric discharge devices with valve action effect the control of the rectification in the manner that the electric circuit externally of the electric discharge device is kept permanently closed and that the switching in at any moment 35 within the half wave of the alternating voltage is effected by establishing the conductivity of the electric discharge device at the moment in question. To this end, either a mercury cathode is caused to emit electrons when ignited by starting electrodes, immersion electrodes or the like or a control grid which is impressed at the moment of ignition with a control potential which initiates the conducting period is arranged in the electric discharge device between the anode and 40 a continuously electron emitting cathode. Characteristic of these prior art devices, and by which they are distinguished from the present invention, is that the electric discharge device in question is already conductively connected to the alternating-current supply circuit before the ig- 45

nition takes place or at least from the moment at which a starting of the arc is possible. The anode of a mercury vapor rectifier which is, for instance, ignited when the alternating supply voltage attains the maximum value, is already 5 impressed a relatively long time with the full anode voltage or—in the case of polyphase rectifiers—with the difference between the voltages of two successive anodes.

The invention differs fundamentally from this 10 method by the fact that the electric discharge device is only switched in the circuit at the moment of ignition or immediately prior thereto by a circuit breaker of any type arranged externally 15 of the electric discharge device. In this manner the advantage is obtained that during the stop phase of an electric discharge device no trouble 20 may arise owing to undesired voltage stresses of the anodes. Furthermore, the invention has the advantage that the type of the rectifier device 25 may be far more liberally chosen than has hitherto been the case. The controllable rectification has hitherto been possible only by the use of tubes which operate with controllable electric discharge devices, i. e., for instance, with 30 vacuum tubes, such as mercury vapor discharge devices. The invention renders for the first time possible the use of known dry rectifiers and the utilization of their advantages in operation for 35 the controllable rectification.

While in the conversion of polyphase currents for each phase a separate valve may be provided, an arrangement is also possible in which only two valves are used or, generally speaking, in 35 which the number of valves is equal to the maximum number of phases which carry simultaneously current of the same direction. Circuits involving this feature are known in the art. As soon as the current has ceased to flow in one phase, the valve is disconnected from this phase 40 and may now be switched over to another phase which commences to carry current at a later time. In the customary rectifier arrangement in which at most, namely during the overlapping period, two phases partake simultaneously in the 45 current supply, the valve which first ceases to supply current is then connected to the phase which is second next in the sequence of current-carrying phases. In case transformers are used which, due to their particular circuit arrangement, permit an increase in the current flow periods of the individual phases the number of valves must be correspondingly increased, so 50 that the individual phase currents may always flow over one valve. By the reduction in the 55

number of valves and the incidentally required switching over of the valves, however, no fundamental change is brought about in the rectifying process or in current or voltage curves of the converter system. Above all it is possible, the same as in the arrangements which provide an individual valve for each phase, to control the voltage, delivered by the converter, by shifting the closing time of the valves within the range 5 of the voltage half wave within which a given phase may carry any current at all.

By reducing the number of valves, the total amount of apparatus is reduced, so far as the provision for valves is concerned. It is true, in 15 such cases each valve is inserted in circuit more often and therefore it must be dimensioned somewhat larger so far as its current-carrying capacity is concerned, but this necessary increase in size of the individual valves has not nearly the 20 economic effect on one side as the reduction in the number of valves on the other side. The reason for this may be found in the fact that in case of a smaller number the valves are now subject to more uniform loads, so that the mean 25 value of the valve current in relation to the best effect, so far as heating and losses are concerned, increases.

Since the total time, during which a phase of a polyphase rectifier carries current is practically 30 independent of the degree of control of a half wave, the time interval between the switching in and switching out of an alternating-current phase remains always constant. Only under particular circumstances, for instance when converting direct current into alternating current, it may be preferable to control this time interval by making it conditional, for instance, upon one or more of certain operating conditions, for instance, upon the load current of the converter. In general, a simple switching gear between the 35 rectifier units and the alternating-current source is sufficient; for instance, a revolving switching gear which is designed in the form of a commutator provided with stationary brushes and which is driven by a synchronous motor connected to the alternating-current supply circuit.

Here it may be mentioned that it is quite immaterial by what type of circuit breaker the connection between the alternating-current phases 40 and the electric discharge devices is established and broken. Mechanical switching gears with direct contact between stationary contacts or also switching gears may be employed in which either 45 contact is replaced by a liquid electrode. Switching gears of this type, for instance, in the form of electrolytic circuit breakers or mercury jet circuit breakers have hitherto been employed for other converting purposes. At all events, a 50 switching gear must be inserted between the alternating-current source and the rectifier units, which gear establishes and breaks at the proper time the conductive connection between the rectifier unit and the alternating-current source. 55 To facilitate the switching operation, condensers are preferably connected in parallel relation to the contacts or other protective means, such as series reactors or series resistors are employed.

For a further understanding of my invention 60 reference may be had to the following description taken in connection with the accompanying drawings, in which—

Fig. 1 shows diagrammatically a six-phase rectifier arrangement employing dry rectifier units, 65 Fig. 2 shows the cylindrical rotary switch gear

4 of Fig. 1 developed in a plane, and indicates the interconnection between the several contact elements,

Fig. 3 shows a modified form of Fig. 1 in which the secondary of the transformer is divided, 5

Fig. 4 shows a controllable dry rectifier system for exchanging energy between an alternating current supply circuit and a direct current consuming device,

Fig. 5 shows a rectifier system employing a 10 double anode mercury vapor rectifier, and

Fig. 6 shows the invention applied to an inverter.

Referring now to Fig. 1, this figure shows a six-phase rectifier with dry rectifiers. The primary winding of the transformer 2 is connected to the three-phase supply circuit 1, the secondary, six-phase winding 3 of the transformer being connected to the switching gear 4. The latter is driven by a synchronous motor 5 which is 20 connected to the three-phase supply circuit 1 through an induction-voltage regulator 7 in order that the synchronous position of the contact movement may be varied. The switching gear 4 consists of a contact drum cooperating with a 25 number of brushes. Six of the brushes are connected in cyclic sequence to the six phases of the transformer winding 3, whereas each of the other two brushes is connected to the positive conductor of the direct-current circuit 8 through one of the 30 rectifier units 6. In this case the brushes connected to the rectifier units, contact with the complete slip rings 9 and 10, whereas the segmented contact rings which cover only a portion 35 of the periphery of the contact drum are allotted to the other brushes. The contact drum is shown developed in Fig. 2. As will be seen from this figure at most two phases of the transformer winding 3 are connected to one rectifier unit at a given time moment by the switching gear cooperating 40 with the rectifier units 6. During the greater portion of the rectifier flow phases only one transformer phase is switched in. The individual contacts overlap one another in the direction of rotation so that also the flow periods of the individual phases overlap one another. The overlapping of the switching-in periods is necessary 45 on account of the commutation.

The moment, at which the switching in takes place within the half cycle of the alternating 50 voltage of the alternating-current supply circuit 1, is adjusted by varying the relative position between the revolving system and the vector of the alternating-current supply circuit 1. To this end, various known means are available: Either an 55 induction-voltage regulator 7 shown in Fig. 1, or a displacement of the stator of the synchronous motor 5, or a variation of the excitation of the part-windings in the direct-current exciting circuit of this motor, by means of which the vector 60 position of the excitation is displaced with respect to the supply circuit vector.

It may be further added that the invention is also applicable to converters operating with dry rectifiers if one rectifier unit is allotted to each 65 alternating-current phase.

In Fig. 3 is shown an embodiment for a controllable dry rectifier employing a transformer connection in which the duration of flow phase of the rectifier is increased by making use of the 70 known interphase choke coil. In this case two secondary three-phase windings 12 and 13, which are each star-connected, are provided. These windings are phase differentiated 180° and supplement one another to a six-phase system and 75

are associated with the primary winding 11 of the transformer. Between the neutral points of both secondary windings is arranged the choking coil 14 whose center represents the neutral point 5 of the entire secondary transformer winding. This arrangement of the divided secondary winding has the effect that the two secondary three-phase systems operate independent from one another, though they supplement one another to a 10 secondary three-phase system. The switching gear 145 is shown schematically and may be designed in any suitable manner. Since in this case three phases of the entire transformer secondary winding carry current at 15 the same time, also three rectifier units 16 must be provided. These units are so connected to the break contacts of the switching gear 15 that the units are successively connected to three successive phases of the secondary winding of the transformer. In general, also in this case the entire switching gear between the transformer and the rectifier units must be designed so that it connects the individual transformer phases cyclically in succession.

25 Instead of the choking coil 14 shown in Fig. 3 also other known devices serving the same purpose, for instance, magnetically interconnected reactors may be employed in the individual phase conductors.

30 Fig. 4 shows the regulable dry unit rectifier for exchanging energy between an alternating-current supply circuit 1 and a direct-current consuming device 17. The connection of the entire arrangement corresponds to the cross-connection 35 employed in other regulable rectifiers, whereas each rectifier unit is connected in a manner corresponding to the connection shown in Fig. 1. Accordingly, the primary winding 18 of the transformer is coupled with two secondary windings 19 and 20 each of which in the embodiment shown in Fig. 4 is star-connected in six phases. To each transformer winding is allotted a particular switching gear 23 and 24 respectively which is driven through an induction voltage 40 regulator 25 and 26 respectively, and each switching gear is arranged in series with a pair of dry rectifier units 21 and 22 respectively. The connection according to Fig. 4 may also be employed to connect a direct-current supply circuit to an 45 alternating-current supply circuit and to exchange energy in any direction between the two supply circuits.

In Fig. 5 is shown an embodiment of the invention in which a double anode mercury vapor discharge device 27 is employed to take the place of two separate rectifier units such as in Fig. 1. The connection between the two individual anodes of the electric discharge device and the switching gear is the same as that shown in the 50 connection according to Fig. 1. The two electric discharge devices embodied in tube 27 are provided with control grids 35 which in order to be protected against disturbances may be connected to a negative inverse voltage source 28 through 55 a relay arrangement 29. The same control grids may also be employed to ignite the electric discharge devices at the beginning of the flow phase. In this arrangement the electric discharge is switched in by the revolving contact 60 device 4 and then immediately ignited by correspondingly influencing the control grids. In the connection according to Fig. 5 it is assumed that the control grids 35 are controlled through a revolving contact device 28 which as well as the 65 switching gear in the anode circuits of the elec-

tric discharge devices is driven by a synchronous motor 5. Instead of the control grids also other means, for instance, starting electrodes immersed in the mercury may be employed. The two-anode discharge device 27 shown in Fig. 5 may be replaced by two single-anode units. If divided transformer secondaries with choking coils or the like, such as in Fig. 3, are employed the number of the electric discharge units must be correspondingly increased the same as in the connection shown in Fig. 3.

70 Fig. 6 shows the invention as applied to an inverter. Also in this case electric discharge units 31 and 32 are connected to the secondary winding 3 of a polyphase transformer through a switching gear 30 in the same manner as in the connection according to Figs. 1 or 5. Condensers 33 are arranged between the anodes of the two electric discharge devices. Such condensers are, however, only necessary if the inverter is connected to a separate alternating-current supply circuit, that is if there is no alternating voltage independent of the inverter available in the alternating-current supply circuit 1 in order to control the quenching of the electric discharge 75 devices. As will be apparent from the connection shown in Fig. 6 the means employed according to the invention in the polyphase inverter are very simple. The two electric discharge units 31 and 32 of the inverter are equipped with control grids 34 which in turn are connected to a control voltage source 14 and which have the same controlling functions as the grids 35 of the electric discharge devices in Fig. 5. Instead of the electric discharge devices shown in Fig. 6 also dry rectifiers or other non-controllable electric valves may be employed in this connection.

80 The converter according to the invention may easily be dimensioned also for high voltage; in this case care should be taken to provide sufficient insulation of the contact device through which the rectifier units are connected to the secondary windings of the transformer. Both the stationary and the revolving contacts may be secured to high voltage insulators. Since the 85 rectifier units are not impressed with any voltage during the stop phase, the voltage stress is considerably smaller; accordingly the rectifier units may be designed with correspondingly smaller dimensions, which is particularly advantageous in the case of high voltages. In such rectifiers backfires are also eliminated. In this case it is of particular advantage to employ besides the contact devices also control grids as above described in connection with Fig. 5.

55 I claim as my invention:

1. In a converter for exchanging energy between a polyphase alternating current supply circuit and a direct current consuming circuit, a transformer having its primary winding connected to said alternating current circuit and having two secondary windings, two groups of rectifiers and a switching gear for each secondary winding having contacts and associated circuits for connecting the phases of each of said secondary windings in succession with timely overlapping through its switching gear to one group of said rectifiers and for connecting said rectifier groups in opposite flow directions to the two poles of said direct current consuming circuit, means 60 for operating the contacts of said switching gears in synchronism with the frequency of said alternating current supply circuit, and means for varying in each switching gear the closing time of its contacts with respect to the voltage cycle of 65 70 75

said alternating current within a portion of said cycle which represents the actual current flow phases of the rectifiers of the appertaining group.

2. In a converter for exchanging energy between a polyphase alternating and a direct current circuit, a plurality of gas discharge rectifiers connected at similar poles to one pole of said direct current circuit, a switching gear having contacts connectable in series with the other poles of said rectifiers, and associated circuit connections for connecting the several phases of said alternating current circuit through said switching gear to the other poles of said rectifiers, means for actuating the contacts of said gear in synchronism with the frequency of said alternating current circuit, means for varying the closing time of said contacts with respect to the voltage cycle of said alternating current within a portion of said cycle which represents the actual current flow phases of said rectifiers, a circuit connection between said rectifiers for connecting them in series with opposing polarity, and a condenser in said connection suitably dimensioned to alternately quench said rectifiers at the ends of their flow phases.

3. In a converter for exchanging energy between a polyphase alternating and a direct current circuit, a transformer having its secondary winding divided into a sufficient number of phases to permit the simultaneous switching in of a desired number of similar current-carrying phases, a plurality of rectifiers equal in number to the number of said simultaneous current-carrying phases, a switching gear having contacts connectable in series with said rectifiers, said switching gear being designed to cyclically close its contacts during overlapping closure periods the length of which is smaller than half the period of the voltage cycle of said alternating current, circuit connections for connecting the several phases of said secondary transformer winding through said switching gear to said direct current circuit so as to form within the simultaneously switched-in phases short circuit paths including said rectifiers, each path including two rectifiers having opposite conducting directions, means for actuating the contacts of said gear in synchronism with the frequency of said alternating current circuit, and means for shifting the closure periods of said contacts with respect to the voltage cycle of said alternating current within a portion of said cycle which represents the actual current flow phases of the rectifiers so as to control the energy exchanged between said alternating and said direct current circuit.

4. In a converter for exchanging energy between an alternating and a direct current circuit, a plurality of gas discharge rectifiers connected at similar poles to one pole of said direct current circuit, a switching gear having contacts connectable in series with the other poles of said rectifiers, and associated circuit connections for connecting the several phases of said alternating current circuit through said switching gear to the other poles of said rectifiers, means for actuating the contacts of said gear in synchronism with the frequency of said alternating current circuit, means for varying the closing time of said contacts with respect to the voltage cycle of said alternating current within a portion of said cycle which represents the actual current flow phases of said rectifiers so as to control the energy exchanged between said alternating and said direct current circuit, auxiliary electrodes and a voltage source for said electrodes for controlling the oper-

ation of said rectifiers, and means connected with said auxiliary electrodes for rendering said rectifiers inoperative in case of excess current.

5. In a converter for exchanging energy between an alternating and a direct current circuit, a plurality of gas discharge rectifiers connected at similar poles to one pole of said direct current circuit, a switching gear having main contacts connectable in series with the other poles of said rectifiers, auxiliary contacts, and associated circuit connections for connecting the several phases of said alternating current supply circuit through main contacts of said switching gear to the other poles of said rectifiers, in combination with means for actuating main and auxiliary contacts of said gear in synchronism with the frequency of said alternating current circuit, means for varying the closing time of said contacts with respect to the voltage cycle of said alternating current within a portion of said cycle which represents the actual current flow phases of said rectifiers, auxiliary electrodes and a voltage source for said electrodes for controlling the operation of said rectifiers, said auxiliary electrodes being controlled by said auxiliary contacts of said gear to effect the ignition of said rectifiers before the closing time of said main contacts.

6. In a converting arrangement for exchanging energy between an alternating current circuit and a direct current circuit, in combination, a set of electrical valves of uncontrollable type, said valves being arranged between said alternating and said direct current circuits so as to establish a rectifying connection, a commutating contact device series-connected with said valves at the alternating current side of said valves, said device being designed for connecting in timely succession several phases of said alternating current circuit with said valves in synchronism with the alternating current, and means for controlling the energy exchanged between said circuits, said means comprising a device for shifting the phase position of the contact closing periods of said device within the periods in which the voltage in said phases corresponds with the conductive direction.

7. In a converting arrangement for exchanging energy between an alternating current circuit and a direct current circuit, in combination, a plurality of dry rectifiers equal in number to the number of simultaneous current-carrying phases of said alternating circuit, a commutating contact device series-connected with said rectifiers in said alternating current circuit, associated circuit connections for connecting several phases of said alternating current circuit through said device and said rectifiers with said direct current circuit, a synchronous drive for operating said device with the frequency of said alternating current, and means for controlling the energy exchanged between said circuits, said means comprising a device for varying the phase position of said drive so as to shift the contact closing periods of said device within the periods in which the voltage in said phases corresponds with the conductive direction of said rectifiers.

8. In an arrangement for exchanging energy between an alternating current circuit and a direct current circuit, a group of electric valves connected between said two circuits, control means for periodically establishing the conductive condition of said valves, a commutating contact device having contacts series connected with said valves and associated circuit connections for connecting the phases of said alternating current circuit through said contact device to said valves

5 in timely overlapping succession, drive means for actuating said contact device in the frequency of said alternating current circuit, said control means and said drive means being inter-coupled so as to effect the closing of said contacts at a moment within a period in which the valves connected to said contacts are in conductive condition and the conductive direction corresponds to the direction of the voltage at said contacts, and
10 means for shifting the closing moments of said contacts within said period.

15 9. In an arrangement for exchanging energy between an alternating and a direct current circuit, a plurality of electric rectifiers connected between said two circuits, a commutating switching gear having contacts connectable in series with

said electric rectifiers and associated circuit connections for connecting several phases of said alternating current circuit through said switching gear to said rectifiers in timely overlapping succession, means for actuating the contacts of the 5 switching gear in synchronism with the frequency of said alternating current circuit, said means being designed to close each contact within a period in which the rectifier in the phase connected to said contact is conductive in the direction of the voltage in said phase, and means for controlling the power output of the arrangement, said control means comprising a device for displacing the closing time of said contacts within said period.
